COMBINED BENCH AND SEAT UNIT

William E. Miller, 441 Niles-Cortland Road NE.,
Warren, Ohio

Filed Sept. 4, 1959, Ser. No. 57,429

Term of patent 14 years

(Cl. D33—14)

Figure 1 is a perspective view of a combined bench and seat unit, showing my new design,

The dominant features of the design are shown in full lines in the drawing.

I claim:

The ornamental design for a combined bench and seat unit, substantially as shown and described.
